REMOVABLE HEADSHAFT ASSEMBLY FOR
REFUSE VEHICLESErnest C. C. Miller, Laurelton, and John P.
Calamore, Kew Gardens, N. Y.

Application June 23, 1949, Serial No. 100,908

4 Claims. (Cl. 214—67)

1

This invention relates to improvements in a refuse collecting truck, of the type provided with a power driven endless conveyor for loading material into the truck, and more particularly to an improved means for mounting the headshaft of the conveyor so that it may be easily removed as a unit when it becomes necessary to repair it or to renew any of its components.

In previous refuse collecting trucks of this type, an example of which is disclosed in U. S. Letters Patent No. 2,224,789, issued on December 10, 1940, to Loron G. Kurtz and Carl C. Ottoson, the headshaft extended through the sidewalls of the truck body journalled in bearings mounted on the outside of these walls, these bearings being so mounted in order to protect them from dirt from the refuse carried by the endless conveyor, and also to make them readily available for routine inspection and lubrication. However, it was found that when the sprockets which are keyed on the shaft to drive the conveyor became rusted in place it was necessary to cut the shaft in two pieces in order to remove it; this of course was an extremely wasteful procedure.

A further objection to the previous mounting means was the fact that whenever a repair necessitated the removal of the headshaft, it required the entire truck to remain in the shop during the time spent in making repairs to the headshaft alone. Due to the wear to which the headshaft and its sprockets are subjected when in operation, and their relatively close proximity to the refuse as it accumulates inside the truck they require more frequent replacement than other parts of the truck, and the presence of an otherwise serviceable truck in the repair shop often overcrowded the shop facilities.

It is therefore an object of the present invention to provide a mounting assembly for the conveyor headshaft bearing of refuse collecting trucks of this character which may be easily removed as a unit, thereby permitting a serviceable unit to be substituted in its place.

It is a further object to provide a mounting assembly for a headshaft of this type which may extend beyond the sidewalls of the body so as to be supported by bearings on the outside of the walls, which may be easily and quickly removed as a unit and without cutting the shaft.

Briefly stated, these and other desirable objects are accomplished by forming the sidewalls in a plurality of sections which are detachably supported so as to permit the headshaft to project through the sidewalls at points along the line of demarcation between the sections of the sidewall.

5 The journal mountings being also detachably secured to one or more of the sidewall sections, it is only necessary to separate the sections between which the shaft extends in order to remove it.

10 The general features of the invention having been thus outlined, further advantages of structure and operation will be described in connection with the appended drawings illustrating a preferred embodiment of the invention, in which:

15 Fig. 1 is an elevation of a refuse truck having the improved mounting means for the headshaft; Fig. 2 is an enlarged detailed elevation of a portion of the sidewall of a truck showing the disposition of various elements of the mounting means; Fig. 3 is a cross-sectional plan view of the device taken on the line 3—3 of Fig. 2; Fig. 4 is similar to Fig. 2 except that it shows the sidewall with the headshaft assembly removed.

20 Referring now to the drawings in detail, Fig. 1 illustrates a refuse collecting truck having a loading boot 5 situated at the rear end into which refuse is deposited by the employees, from which an endless conveyor, indicated at 6 by dotted lines

15, which is located within the body of the truck, carries it into the upper portion of the body from which it drops into the main body of the truck. As indicated, the conveyor 6 is housed principally within a housing running along the upper portion of the truck and having sidewalls 7 and 8. Near the forward portion of the sidewalls the conveyor 6 is carried by a removable headshaft assembly indicated generally at 6a, which includes sprockets 9, suitably keyed to a shaft 10, the ends of which project beyond the walls 7 and 8 and are supported by journal means such as ball bearings 11 and 12 suitably secured to mounting plates 13 and 14 respectively.

25 In order to protect as much as possible against the entry of refuse into the working parts of the headshaft assembly an apron member 15 encircles the shaft 10 over substantially its entire length between the sprockets 9, and the shroud members 16 and 17 cover exposed portions of the sprockets. The apron 15 is provided near its forward edge with a laterally extending cylindrical passage 18 which allows it to be supported at that edge on the rotating shaft 10, while the rearwardly disposed tail portion 19 rests on cross-member 20 and is provided on its underside with an elongated plate member 21 having a downwardly offset center section 22 which passes beneath the cross-member 20 and may be detachably secured as by means of bolts 23 to permit fore-and-aft movement of the apron 15.

The shroud members 16 and 17 may be welded to plates 24 and 25 respectively.

Details of the mounting of the assembly in the sidewalls are shown in Figs. 2 and 4, in which only the right hand side may be seen; however, it will be understood that the arrangement of parts on the left hand side will be similar. In Fig. 4 the sidewall 7 is shown provided with a recess depending from its upper margin, the front and rear edges of this recess being defined by stiffening members such as angle irons 26 and 27 respectively. The lower edge of the recess may be defined by a plate member 28 whose upper edge includes a substantially horizontally extending cut-out portion 28a which lies below the shaft 10 and permits certain limited fore-and-aft movement of the shaft assembly. The upper portion of the recess is closed by a removable plate member 29 having outwardly turned flanges 30 and 31 enabling it to be attached, as by means of the bolts 32, to the angle irons 26 and 27 in alignment with the plate member 28, with its lower edge 29a passing above the shaft 10. The horizontally disposed slotted openings 28b and 29b are provided respectively in plate members 28 and 29 to receive the mounting bolts 33, threaded to receive removable nuts 34 for limited fore-and-aft displacement as will be explained. When in position the bolts 33 on the right hand side of the device pass through openings provided in the shroud 16 and mounting plate 13 in alignment with the slotted openings 28b and 29b, while on the left hand side of the device the bolts 33 pass through similar openings provided in the shroud 17 and the mounting plate 14.

Referring again to the right side of the device, as shown in Fig. 2, for a detailed study of its construction, but with the understanding that similar construction is applied to the left hand side, it will be seen that when the nuts 34 are drawn up on the bolts 33 the mounting plate 13 and the shroud 16 may be firmly supported in the sidewall 7 by the plate members 28 and 29. Furthermore, if the nuts 34 are loosened, but not removed, the bolts 33 carrying the mounting plate 13 and the shroud 16 in fixed relationship to each other may be moved horizontally as a unit in the slotted openings 28b and 29b. Inasmuch as the conveyor 6 lies in a horizontal plane extending rearwardly from the headshaft assembly 6a, the horizontal shifting of the mounting plates 13 and 14 which support the journal means 11 and 12 for the shaft 10 and the conveyor carrying sprockets 9 will effect variations in the tensioning of the conveyor 6, because the slotted openings 28b and 29b extend substantially in the direction of the thrust force exerted by the conveyor. To assist in the adjustment of the headshaft assembly 6a and to resist this force, thrust reaction elements indicated generally at 35 and 36 may be provided at each end of the shaft 10. In the embodiment shown these elements are in the form of elongated rods which are threaded at both ends to receive adjusting nuts 35a and 36a and locking nuts 35b and 36b. On the right hand side one end of the reaction element 35 is connected to the sidewall 7 by means of a bracket 37 and the other end is connected to the mounting plate 13 by an outwardly extending lug 38, while on the left hand side the reaction element 36 extends between the bracket 39 attached to the sidewall 8 and the lug 40 on the mounting plate 14. In the preferred embodiment as shown the

reaction elements 35 and 36 offer an unyielding resistance to the thrust force exerted by the conveyor 6, but it will be understood that when it is desired the elements 35 and 36 may be modified so as to have a limited contractible movement offering a yieldable resistance to the thrust force of the conveyor. Additional support for slideable movement of the mounting plates 13 and 14 may be provided in the form of horizontally disposed rail elements 41 welded to the supporting plate members so as to overlie the upper and lower edges of the mounting plates.

The sidewalls 7 and 8 are joined by a top wall 42 forwardly of the headshaft assembly 6a, and by a top wall 43 rearwardly of the assembly, while a removable top cover plate 44 encloses the opening thus provided between the forward and rearward top walls to make the entire body of the truck relatively dust tight and present a smooth unbroken surface along the upper surface.

A power driving device, indicated generally at 46, may be included in the headshaft assembly 25 supported in a housing 47 on the mounting plate 13. The power driving device forms no part of this invention and may take several forms. In the preferred form as shown it comprises an hydraulic motor 48 provided with conduits having detachable couplings 49 and 50 for suitable connection to a source of fluid under pressure (not shown) normally carried by the truck, and having an output shaft 51 in alignment with, and connected to, the shaft 10 by a coupling 35 means 52.

The procedure for removing and replacing the headshaft assembly as a unit will now be described. The fluid couplings 49 and 50 having been detached the cover 44 is removed by taking out the bolts 45, after which the nuts 34 are unscrewed and the bolts 33 removed. The locking nuts 35b and 36b are then loosened on the elements 35 and the nuts 35a and 36a are run in toward the center to allow the mounting plates 13 and 14, carrying the shaft 10, to slide rearwardly in the rails 41 under the influence of the force caused by the tension in the conveyor 6 until this tension is reduced to the point where the elements forming the conveyor can be separated and removed from the sprockets 9 in a manner well known in the art and forming no part of this invention. After the conveyor 6 has been removed, the thrust reaction elements 35 and 36 can be separated from the headshaft assembly 6a and/or the sidewalls 7 and 8 by removal of the appropriate set of locking nuts 35b or 36b. At this point, there being no reactive force present the shaft assembly will remain in position at any point in the lower rails 41, and the plate members 29 may be raised vertically after the bolts 32 have been removed. In addition, at some point in the operation it is necessary to remove the center section 22 from the apron 15 by removing the holding bolts 23. These operations having been performed, it is then possible to raise, as a single unit, the shaft 10 with the journal means 11 and 12, the mounting plates 13 and 14, the shrouds 16 and 17, and the power device 46 still secured to it, 70 in a vertical direction completely out of the truck body.

To replace the headshaft assembly it is only necessary to perform the operations noted above in the reverse order, bearing in mind the fact 75 that the nuts 34 are not to be tightened until

the conveyor 6 has again been placed on the sprockets 9 and the tension applied to the conveyor adjusted by means of the thrust receiving elements 35 and 36. This adjustment having been made, the nuts 34 may be tightened on the bolts 33 to draw the mounting plates 13 and 14, and the shrouds 16 and 17 into tight frictional engagement with the plates 28 and 29 which will relieve the elements 35 and 36 from taking the entire thrust load caused by the operation of the conveyor 6.

While the present preferred embodiments of the invention have been illustrated in considerable detail, it should be understood that the invention is not to be limited to these arrangements, but may be carried out in other ways.

We claim as our invention:

1. A headshaft mounting for refuse collecting trucks having an endless conveyor disposed in a body portion having spaced sidewalls, said sidewalls being provided with a downwardly extending recessed portion in the upper edge extending below said headshaft, said headshaft projecting outwardly of the sidewalls, a removable plate for enclosing the recessed portion above the shaft, journal means for the ends of the shaft, and fastening means for detachably securing the journal means to said spaced sidewalls and said removable plates in a plurality of positions to take up slack in the conveyor.

2. A removable mounting for an endless conveyor headshaft assembly disposed in the body of a refuse collecting truck having spaced vertical wall sections, comprising a plate member substantially coplanar with one of the vertical wall sections and detachably secured thereto, a conveyor headshaft extending between said plate member and the other of the vertical wall sections, journaled support means for said headshaft, supporting means for detachably securing said journaled support means to said plate member and said other vertical wall section in a plurality of positions in the direction of thrust of said conveyor, and adjustable thrust-receiving means for positioning said journaled support means.

3. In a fully enclosed refuse collecting truck body having spaced sidewalls, said body being pro-

vided with an access opening in an upper portion depending downwardly into a margin of the sidewalls to receive headshaft assembly means including a shaft to project outwardly of said access opening, the combination including, closure means for the access opening including a removable plate to be disposed substantially coplanar with a side wall, adjacent margins of said plate and a sidewall defining an opening through which said shaft projects, one of said margins being longitudinally recessed to permit translatory movement of said shaft for adjusting slack in a conveyor, journal means for the shaft, and adjustable thrust-receiving means for positioning the journal means.

4. In a refuse collecting truck body having spaced sidewalls, said sidewalls being provided with a downwardly reentrant marginal portion, headshaft assembly means to be received within said body having a shaft to project outwardly through said reentrant marginal portion of a sidewall, a plate member adapted to be removably secured to a sidewall to bridge the reentrant marginal portion above said projecting shaft, one of the margins of an element adjacent said shaft being provided with a longitudinally disposed recess to permit translatory movement of the shaft for adjusting slack in a conveyor, journal means for the shaft, one of said adjacent members being provided with a slotted aperture to receive fastening means for the journal means, and thrust-receiving means for positioning the journal means.
